UNITED STATES PATENT OFFICE

145,984

DESIGN FOR AN AUTOMOBILE

Willie Reed, Memphis, Tenn., assignor of one-half to C. C. Jackson, Memphis, Tenn.

Application November 20, 1945, Serial No. 123,929

Term of patent 7 years

(Cl. D14—3)

To all whom it may concern:

Be it known that I, Willie Reed, a citizen of the United States, residing at Memphis, in the county of Shelby and State of Tennessee, have invented a new, original, and ornamental Design for an Automobile, of which the following is a specification, reference being had to the accompanying drawings, forming a part thereof.

I claim:

The ornamental design for an automobile, as shown and described.

WILLIE REED.
